UNITED STATES PATENT OFFICE.

DUNCAN E. WILLIAMSON, OF SEGUIN, TEXAS.

PRESCRIPTION FILE.

Application filed April 3, 1924. Serial No. 704,012.

To all whom it may concern:

Be it known that I, DUNCAN E. WILLIAMSON, a citizen of the United States, residing at Seguin, in the county of Guadalupe and 5 State of Texas, have invented certain new and useful Improvements in Prescription Files, of which the following is a full, clear, and exact description.

This invention relates primarily to a filing cabinet for physicians' prescriptions and has for its object to provide such a device which is entirely enclosed and yet which is freely accessible to the druggist when it is desired to refill any particular 15 prescription.

Another object of the invention resides in the provision of such a device which will function even though several of the cabinets are stacked in a vertical tier without the 20 necessity of removing them from the stack.

A further object of the invention consists of a cabinet provided with a vertically swinging door hinged in such manner as to be horizontally supported when swung to 25 an open position.

A further object of the invention consists in the provision of an improved file cabinet which is composed of a very few parts which are easily and cheaply manufactured and readily assembled.

Other objects and advantages of the invention will be apparent from the following description when taken in connection with the accompanying drawings; in which,

35 Figure 1 is a perspective view of the cabinet in open position.

Figure 2 is a side elevation of the file proper, partly in section.

Figure 3 is an enlarged vertical section 40 through a portion of the base-board, and

Figure 4 is a fragmentary section through a portion of the box.

Referring to the drawings more in detail, the numeral 1 indicates generally the file 45 cabinet or box which may be made of wood or metal as desired and which is provided with a front opening 2 adapted to be closed by a vertically swinging door 3 hinged to the base of the cabinet as indicated by the numeral 4. In the specific embodiment shown 50 it is desirable that the door be held in a horizontal position and to this end I have provided a lug 4' which is adapted to be engaged by the door as shown in Figure 4. A latch 13 is provided for normally holding the door in closed position,

The file proper comprises a base-board 5 of substantially the inner dimensions of the bottom of the box. This board 5 is adapted to slide in and out of the box and has 60 mounted thereon the divided loop 6 which comprises the legs 7 and 8 and overlapping fingers formed on the upper ends thereof. For the purpose of fixedly securing the loop 6 in place on the base-board and to 65 maintain the legs 7 and 8 thereof in the inclined positions shown, the board is formed with the two inclined apertures 9 and 10 and connecting channel 11. In assembling these two elements it will be apparent that 70 the legs 7 and 8 will be passed up through the apertures 9 and 10 respectively, until the connecting member 12 of the divided loop is seated in the channel 11. Obviously the inclination of the apertures 9 and 10 will 75 greatly assist in retaining the legs 7 and 8 in their normal positions and will tend to prevent the legs from becoming permanently sprung to the outward positions to which they are necessarily moved when a paper 80 is being placed on the file.

In operation, when it is desired to remove or apply a prescription on the file, the door 3 is swung to its horizontal position in which position it is supported by the lug 85 4'. The base-board 5 is then drawn outward and supported on the door 3 as clearly indicated in Figure 1. The legs 7 and 8 may now be sprung slightly apart and the paper applied or removed as desired. It 90 will be apparent that this construction will function equally well where several of the cabinets are arranged in a vertical stack since movements of the door 3 and base-board 5 in no way disturb the top of the 95 box.

In accordance with the patent statutes, I have described what I now believe to be the best embodiment of the invention, but I do not wish to be understood thereby as limiting myself or the scope of the invention, as many changes and modifications may be made without departing from the spirit of the invention; all such I aim to include in the scope of the appended claims.

Having fully described the invention, what I claim as new and desire to secure by Letters Patent is:

1. A file cabinet including a box provided with a front opening, a door for closing 110 said opening, a hinge for attaching said door adjacent the bottom of the opening,

and a lug attached to the box and arranged to support the door horizontally and flush with the bottom of the box when in open position, a base-board adapted for sliding movement into and out of said box, and a divided loop secured to said base-board.

2. In a file cabinet, a base-board provided

with a pair of inclined apertures and a channel connecting said apertures, a divided loop including two legs and a connecting member, said connecting member being seated in the aforementioned channel and the legs in the inclined apertures. 10

DUNCAN E. WILLIAMSON.
